(57) **CLAIM**

The ornamental design for a drizzle device, as shown and described.

DESCRIPTION

An applicator for use in applying small amounts of a liquid or a semi-liquid to items, e.g. honey to bread.

FIG. 1 is a perspective view of a drizzle device showing my new design;

FIG. 2 is top plan view thereof;

FIG. 3 is a left side view thereof;

FIG. 4 is a front view thereof; and,

FIG. 5 is a rear view thereof.
